(57) **CLAIM**

The ornamental design for a syringe, as shown and described.

DESCRIPTION

FIG. 1 is a front, side, and top perspective view of a syringe showing the new design, wherein the opposite side and the rear appear the same;

FIG. 2 is a front elevation view thereof, wherein the rear elevation view appears the same;

FIG. 3 is a side elevation view thereof, wherein the opposite side elevation view appears the same;

FIG. 4 is a top plan view thereof; and,

FIG. 5 is a bottom plan view thereof.

The broken lines shown in the drawings illustrate portions of the syringe that form no part of the claimed design.
